UNITED STATES PATENT OFFICE.

NELLIE BLOOM, OF BRIDGEWATER, IOWA.

DESIGN FOR A RABBIT DOLL.

Application filed July 28, 1925. Serial No. 14,242. Term of patent 7 years.

To all whom it may concern:

Be it known that I, NELLIE BLOOM, a citizen of the United States of America, residing at Bridgewater, in the county of Adair and State of Iowa, have invented a new, original, and ornamental Design for a Rabbit Doll, of which the following is a specification, reference being had to the accompanying drawing, forming part thereof.

I claim:

The ornamental design for a rabbit doll, as shown.

NELLIE BLOOM.
